BATTERY CARRIER

Vernon B. Dawson, Wilmington, Del.

Application March 30, 1936, Serial No. 71,622

3 Claims. (Cl. 294—92)

This invention relates generally to lifting devices and more particularly to an improved construction of lifting and carrying strap for storage batteries and the like.

5 Among the principal objects of the present invention is to provide a battery carrier in the form of a strap having terminals at each end thereof for respectively gripping the posts of a battery, the gripping terminals being readily adjustable to fit posts of different sizes and being further self-adjusting, under the weight of the suspended battery, to firmly and securely grip the posts to insure against accidental release of the posts and dropping of the battery.

10 Other objects and advantages of the invention and economies effected by the constructional details of the invention will be apparent more fully hereinafter, it being noted that the invention consists substantially in the combination, construction, arrangement and relative location 20 of parts, all as will be described in the following specification, as shown in the accompanying drawing and as finally pointed out in the appended claims.

15 In the accompanying drawing, which illustrates a preferred construction of the invention:

Figure 1 is a side elevational view showing the carrier of the present invention in its operative relation to a battery to be lifted;

20 Figure 2 is a side elevational view of one of the post-gripping terminals of the carrier;

Figure 3 is a plan view of the terminal shown in Figure 2;

25 Figure 4 is a sectional view of the carrier terminal showing its application to a battery post (also shown in section); and

30 Figures 5 and 6 are plan views, respectively, showing the serrated faces of the top and bottom plate members of the carrier terminal.

35 Referring now to the drawing, it will be observed that the battery carrier of the present invention comprises a lifting and carrying strap 10, preferably formed of leather, webbing or other suitably strong material, to each end of which is secured a terminal device designated generally by the numeral 11. This terminal device, with which this invention is primarily concerned, essentially includes the bottom plate member 12, the top plate member 13, and the ball or link member 14, all of these parts being operatively connected together, as will presently appear, to provide a unitary assembly of which no one part can be displaced or lost.

40 The bottom plate member 12, which is shown in plan view in Figure 6, is provided at its outer

extremity with a perforation 15 of sufficiently large diameter to loosely embrace a battery post of maximum diameter, as when in new and unworn condition. The opposite rear corners of the plate member 12 are, respectively, provided with looped extensions 16—16 which serve as opposed hinge elements for the link member 14, as will appear hereafter. In addition, the member 12 is provided with a square rivet or bolt aperture 17 and also with a series of transversely 10 extending tooth-like serrations 18. These serrations are formed in the upper face of the plate member 15.

45 The top plate member 13 is of generally T-shaped outline, as shown most clearly in Figure 15 5, and is provided in its outer extremity with a semi-circular notch 19 and centrally thereof with a rectangular aperture 20. This plate member 13 is adapted for flatwise disposition upon the plate member 12 in such manner that the apertures 17 20 and 20 of these members are brought into registry with one another, in which position the base portion 21 of the member 13 is disposed between the opposed hinge elements 16—16 of the bottom plate member 12. The under surface of the 25 upper plate member 13 is also provided with a series of transversely extending tooth-like serrations 22 for engagement with the complementally formed serrations in the upper face of the bottom plate member 12. A rivet, bolt or other suitable 30 fastening element 23 is projected commonly through the registering apertures 17 and 20 of the superposed plate members 12 and 13 to hold the latter in the assembled relation shown in Figures 2 to 4, it being noted in this connection 35 that the said securing element 23 is so designed that enough play is left between the parts 12 and 13 as to permit the serrations 18 and 22 thereof to be disengaged from one another preliminarily to adjusting the device to fit a particular battery post. The shank of the rivet 23 is squared so that when projected through the apertures 17 and 20 the members 12 and 13 are maintained against angular displacement in a horizontal plane and yet are permitted a certain amount of 40 relative longitudinal adjustment. It will also be noted that the portion 21 of the upper T-shaped member 13 extends rearwardly a substantial distance beyond the transverse axis of the hinge elements 16—16 of the plate member 12 and that the said hinge elements are so located that their common axis is downwardly offset from the horizontal plane of the main body 45 of the member 12.

50 The ball or link member 14 is provided at one

extremity thereof with a pair of oppositely projecting pins 24 which respectively project through and are journaled within the hinge elements 16 of the plate member 12, said bail 14 being further provided with a slot 25 through which is passed one end of the strap 10, the said end of the strap being thus secured to the bail in any suitable manner. The link member 14 by virtue of its hinged connection with the member 12 is free to move angularly with respect to the latter about the common axis of the pintles 24-24, this action being important as will be seen presently in that it insures that the terminal securely grips the battery post. In this connection, it will be observed that the serrations 18 and 22 of the plate members 12 and 13 respectively are oppositely inclined so that when these serrations are in engagement with each other as shown in Figures 2 and 4, longitudinal separation of the members 12 and 13 is effectually precluded. However, due to the permissible play afforded between these members 12 and 13 by the securing element 23, the members 12 and 13 may be relatively adjusted when the terminal is free of the weight of the battery to decrease or increase the effective diameter of the aperture 15, the degree of this adjustment being governed solely by the limits of the elongated slot 20 in the upper member 13. It will be understood that this adjustment in effective diameter of the aperture 15 is obtained by so shifting the upper plate 13 longitudinally of the bottom plate 12 as to present the semi-circular notch 19 of the plate 13 more or less interiorly of the circumference of the aperture 15 formed in the member 12. This permissible adjustment is represented by the arcuate dotted line shown in the left-hand portion of Figure 3 to produce a decreased effective diameter *b* as against a maximum permissible diameter *a* (see Figure 6).
As appears most clearly in Figure 4, the arcuate notch 19 of the plate 13 is preferably undercut or beveled throughout its extent to provide a sharpened edge 26 for more effectively engaging the wall of the battery post A. Also, as appears most clearly in Figure 4, it will be observed that as the strap 10 is pulled upwardly against the weight of the battery, the link member 14 is necessarily rotated in counterclockwise direction about its hinged axis and engages the inner edge 27 of the member 13 with the consequent result that the said member 13 is forced into intimate engagement with the post A at the same time that the serrations 22 thereof are more firmly pressed against and so more firmly engage the serrations 18 of the bottom plate member 12. Thus, the

weight of the battery itself serves to secure the gripping terminals 11 of the carrier all the more tightly upon the battery posts A. To release the gripping terminals 11 from their respective posts, it is merely necessary to relieve the carrier of the weight of the battery, whereupon the link members 14 drop downwardly and out of engagement with the free edges 27 of the upper members 13, following which the plates 13 and 12 may be readily slipped apart sufficiently to remove the terminals from the posts A.

It will be understood, of course, that the invention is susceptible of various changes and modifications which may be made from time to time without departing from the real spirit or general principles thereof and it is accordingly intended to claim the invention broadly, as well as specifically, as indicated in the appended claims.

What is claimed as new and useful is:

1. In a lifting device, in combination, a pair of members arranged in superimposed relation, one of said members being provided with an aperture therein through which a post or like structure may be projected and the other of said members being adapted for adjustment relatively to said aperture member to more or less cover a portion of said aperture whereby to vary the effective diameter of the opening through which said post or like structure is projected, and means hinged to said aperture member and engaging the other member to maintain the latter in post-engaging position.

2. In a lifting device, in combination, an apertured member adapted to loosely embrace a post or like structure on an article to be lifted, a bail member hinged to one extremity of said apertured member, a lifting strap or handle secured to said bail, said bail and apertured member being relatively so arranged that an upward pull on said strap or handle causes said bail to be angularly rotated with respect to said apertured member, and a second member superimposed upon said apertured member and longitudinally shiftable with respect thereto, the forward edge of said second member being adapted to engage the post embraced by said apertured member and the rear edge thereof being engaged by said bail upon an upward pull of said strap or handle whereby said second member coacts with said apertured member to securely grip said post.

3. A lifting device of the character defined in claim 2 including coacting means in said superimposed members for interlocking the same against unintentional separation.
